UNITED STATES PATENT OFFICE.

FREDERIC HENRY DAY, OF HOPEWELL, VIRGINIA.

CAR-DOOR LOCK AND SEAL.

1,258,659.

Specification of Letters Patent. Patented Mar. 12, 1918.

Application filed September 28, 1917. Serial No. 193,818.

To all whom it may concern:

Be it known that I, FREDERIC H. DAY, a citizen of the United States, and a resident of Hopewell, in the county of Prince George and State of Virginia, have invented a new and useful Improvement in Car-Door Locks and Seals, of which the following is a specification.

My present invention relates generally to means for securing car doors, and more particularly to improvements in car door locking devices embodying a seal in connection therewith, and so constructed as to necessitate the use of a key for unlocking the door in addition to breaking the seal when it is desired to open the car door, my object being the provision of an arrangement whereby to obviate the present conditions under which members of train crews, for instance, may obtain unwarranted access to a car by simply breaking the seal.

In carrying my invention into use, it is my intention to provide station freight agents alone, with keys necessary to unlock the car door, so that even should the seal become broken in transit, either due to accident or to intentional breaking for purpose of robbery, the car door will still resist efforts, by virtue of its key-controlled locking features, at entrance thereto.

In its more specific aspect, my invention resides in the features of construction, arrangement and operation to be now described with respect to the accompanying drawings, forming a part of this specification, and wherein:

Figure 1 is a fragmentary side elevation including a portion of a car side and its door, equipped with my improvements.

Fig. 2 is a horizontal sectional view taken therethrough substantially on line 2—2 of Fig. 1.

Fig. 3 is a vertical section taken therethrough substantially on line 3—3 of Fig. 1.

Fig. 4 is a similar view taken substantially on line 4—4 of Fig. 1, illustrating the parts in locked position.

Fig. 5 is a view similar to Fig. 4 illustrating the parts in unlocked position.

Fig. 6 is a detail perspective view of the lock's arm removed.

Fig. 7 is a detail perspective view of the latch bar removed, and

Fig. 8 is a perspective side view of a car side and its door provided with my im-

provements and illustrating the latter in locked position.

Referring now to these figures, and particularly to Figs. 1 and 2, I preferably utilize a lock arm 10 having an eye at one end by means of which it is pivotally connected to a car door A, the eye receiving the outer portion, for instance, of a U-bolt 12 secured through the door, so as to thus permanently hold the arm in horizontally movable relation and adapt the same to shift flatwise against the adjacent outer face of a car side B at one side of the door A.

At the latter portion of the car side B I utilize a lock casing generally indicated at 13, mounted within a rectangular cut-out portion of the car side of substantially the shape of the lock casing, the latter of which has an enlarged rectangular front plate 14 which I preferably counter-seat within the outer face of the car side and secure by means of bolts 15 extending through the car side, at the same time locking both the bolts 15 and bolts 16, the latter serving to connect the lock casing 13 with its front plate 14, by means of cotter pins or other devices 17 calculated to remove all danger of bodily removal of the lock casing.

The front plate 14 has an intermediate rectangular opening 18 and a key slot 19, the former being positioned to receive the angular keeper 20 of the lock arm 10, projecting laterally from the free end of said arm, adjacent to a handle 21 by means of which the said arm may be readily grasped and moved either to the locked position shown in Figs. 1 and 2, or a released position away from the lock casing.

Within the lock casing 13, a latch bar 22 is pivoted at one end at 23, and has a cut-out portion intermediate its ends forming a beveled surface 24 for engagement with the angular keeper 20, said latch bar 22 normally extending in a substantially horizontal position as indicated in dotted lines 100 in Fig. 1, and resting at its free end upon an internal pin 25 within the lock casing 13, forming a stop, the free end of the said latch bar being acted upon by the free end of a spring 26 secured at its opposite end at 27 within the lock casing, to normally hold the said free end of the latch bar downwardly against the stop pin 25.

Thus, the latch bar normally extends in operative position and when the angular 110

keeper 20 is thrust through the opening 18, it strikes the beveled intermediate portion 24 of the said latch bar and raises the latter slightly against the tension of spring 26, 5 which spring again forces the latch bar downwardly to operative position in engagement with the keeper 20 when the latter is at the limit of its inward movement.

Referring now to Figs. 2 and 7 in particular, it will be noticed that the free end 28 of the latch bar 22 is offset and spaced from the front plate 14 so as to admit of a bridge wall between the same and the said front plate 14, said bridge wall being indicated at 29 in Figs. 2, 4 and 5 in particular, and being itself spaced from the front plate 14 in order to normally protect the latch bar against the action of tools or implements other than a key designed particularly for 15 elevating the same, and as seen generally at 20 30 in Figs. 4 and 5.

At a point intermediate its ends, the lock arm 10 has an outwardly projecting ear 31 provided with large and small openings 32 25 and 33, respectively, this ear being arranged to extend between vertically spaced and similarly shaped ears 34 and 35 projecting laterally from the front plate 14 of the lock casing, and having similar large and small 30 openings. A locking pin 36 is also provided, anchored by means of a chain 37 to a portion of the car side, and movable through the enlarged openings of the several ears 31, 34, and 35 with the lock arm 10 in locked position shown in Figs. 1 and 2, the said pin 36 having a small transverse opening adjacent its free end, which in the operative position thereof shown in Fig. 3, extends below the lowermost ear 35 of the series, for the reception 35 of a portion of the wire 38 to which the seal 39 is applied, said wire being extended through the smaller openings of the several aligned ears including the small opening 33 of the ear 31.

45 In this way the door is not only locked by virtue of the engagement of the latch bar 22 with the lock arm 10, but relative shifting movement of the lock arm is prevented by means of the locking pin 36 and the latter is 50 in turn sealed against removal by the extension of a portion of the wire 38 of the seal 39 therethrough.

It is therefore obvious that by providing only the freight agents at the various stations with keys 30 to the lock, it will be 55 impossible to open the car door in tangent, and great losses by theft of train crews,

tramps, and others, will be avoided, and blame for losses more readily determined and justly placed.

60

I claim:

1. In a device of the character described, a lock arm pivoted at one end and provided with a handle and a laterally projecting keeper adjacent its opposite end, a lock 65 casing having its front plate provided with an opening for the reception of said keeper, a latch bar within the said casing and pivoted at one end, said latch bar having an intermediate beveled portion opposite the opening of its front plate and for engagement with the said keeper of the lock arm, means within the casing to normally hold the said latch bar in operative position and including a spring engaging one side of the latch bar 70 to permit the same to yield in one direction, said lock casing having its front plate provided with a key slot, and a bridge wall within the lock casing, spaced from the front plate thereof and disposed between the 75 front plate and the latch bar, adjacent to the said key slot, for the purpose described.

75

2. In a car door lock, the combination of a stationary lock casing including a key-actuated latch bar and means to normally hold said latch bar in operative position including a spring engaging one side thereof to permit the same to yield in one direction, and a horizontally swinging lock arm pivotally mounted at one end and having its opposite end provided with an angularly disposed handle, and a laterally projecting keeper, the latter of which is movable into the lock casing for the purpose described.

80

3. A car door lock including a lock casing 95 having internal key-actuated locking members and externally projecting and vertically spaced ears, a lock arm pivotally mounted at one end and having a portion adjacent its opposite end arranged to extend 100 into the lock casing for engagement by the key-actuated parts thereof, said lock arm having a laterally projecting ear at an intermediate point for alignment with the ears of the lock casing in operative position, said 105 ears of the lock casing and lock arm having aligned openings, a lock pin for engagement through certain of the openings of the said ears and having an aperture adjacent its free end, and a sealing member for extension through the other apertures of the said ears and through the aperture of the said lock pin.

100

FREDERIC HENRY DAY.
